H. S. POWELL

MUFFLER FOR EXPLOSIVE ENGINES

Filed Oct. 10, 1921

INVENTOR

Herbert Spencer Powell

BY Thomas L. Wilder

ATTORNEY

UNITED STATES PATENT OFFICE.

HERBERT SPENCER POWELL, OF NEW HARTFORD, NEW YORK.

MUFFLER FOR EXPLOSIVE ENGINES.

Application filed October 10, 1921. Serial No. 506,590.

To all whom it may concern:

Be it known that I, HERBERT SPENCER POWELL, a citizen of the United States, residing at New Hartford, in the county of Oneida and State of New York, have invented certain new and useful Improvements in Mufflers for Explosive Engines, of which the following is a specification, reference being had therein to the accompanying drawing.

My invention relates to a muffler for explosive engines, and I declare the following to be a full, clear, concise, and exact description thereof sufficient to enable any one skilled in the art to which it appertains to make and use the same, reference being had to the accompanying drawings in which like reference characters refer to like parts throughout the specification.

The object of the invention is to provide a muffler for explosive engines that is constructed not only with the idea of breaking up the explosive charge as it comes from the engine cylinders before it reaches the outside atmosphere but also with the idea of strengthening and stiffening the partitions that form baffle plates in the muffler, whereby to prevent the vibration of said baffle plates and, thereby, increase the efficiency of the muffler in reducing the sound of the exhaust gases as they come to the atmosphere.

To this end the muffler has a plurality of like sections forming chambers with partitions therein having apertures so located as to break up the explosive charge, as it comes from the engine cylinder before it reaches the outside atmosphere.

Moreover, the partitions, which form baffle plates and undergo considerable strain, are perforated with holes for the passage of the exhaust. They are shown here strengthened or stiffened in a novel manner, whereby to prevent vibration by the aid of annular walls or elongated corrugations that are drawn or punched at right angles to the surface of the partitions and about the several apertures formed in each partition therein. Such walls will lend not only strength and stiffness to said partitions but also will extend the metallic surface to aid in the diffusion of heat.

The object will appear by referring to the drawings in which:

Fig. 1 is a central vertical section of a muffler, showing the novel annular walls or

corrugations about the several apertures of each partition or baffle plate;

Fig. 2 is an enlarged perspective view of a single cup employed in the construction of the muffler;

Fig. 3 is an enlarged detail view, showing a vertical central section of a modified manner of constructing the muffler, parts being broken away;

Fig. 4 is an enlarged detail view, showing a vertical section of the wall of a partition or baffle plate adjacent an aperture, that is employed in the construction of the muffler.

Referring more particularly to the drawings, the muffler is formed with a plurality of cups 1 that provide chambers for the passage of the exhaust gases of explosion. The annular walls of each of the cups 1 are flared out a little at the outer or open ends, as at 2, whereby to form a seat for the edge of 75 the next adjacent cup —1—. The ends of the muffler are closed by the flanged heads 3 and 4. Head 3 has a threaded opening for the attachment of the inlet pipe 5 and head 4 a threaded opening for the attachment of 80 the outlet pipe 6.

The several parts including the cups 1 and heads 3 and 4 are bound together by means of stay rods 7, 7 that pass longitudinally through suitable apertures 14 made in the 85 several cups 1 apertures 14 through which stay rods 7 pass being sufficiently large so that cups 1 will not make contact with stay rods 7, whereby expansion and contraction of cups 1 can take place without bending 90 rods 7. There are also apertures made in heads 3 and 4 for the passage of stay rods 7. The rods 7 are located diametrically opposite each other.

The products of the exhaust gases are received and disbursed to some extent through the first two chambers which have a single large central aperture 12, in each instance to form an expansion chamber. Said aperture 12 is formed in the partition and is 100 surrounded by a wall or corrugation 13 that is formed by pressing or drawing the metal through said partition and at right angles to the plane of the adjacent partition. Said gases are received and disbursed to a still 105 greater extent in the successive chambers each of which has a partition wall forming a baffle plate and in which baffle plate is formed a plurality of small apertures 14 that are disposed in two or more concentric circles 110

about the surface of said baffle plate. The baffle plate adjacent each of the small apertures 14 is formed with an annular wall or corrugation 13 as above with respect to apertures 12.

In operation, the exhaust gases pass through the muffler in the direction indicated by the arrows in Fig. 1. The exhaust is diffused to some extent as it passes through the first two chambers of the muffler and to a still greater extent as it passes through the remaining chambers, where the apertures, though smaller, are more numerous and more widely scattered.

The walls or corrugations 13 surrounding each of the apertures 12 and 14 will strengthen and stiffen the several partitions or baffle plates to such an extent that they will stand up under considerable strain and, thereby, prevent vibration thereof, whereby to prolong the life and efficiency of the muffler, as well as effect a more complete muffling of the sound that the exhaust gases make on reaching the outside atmosphere. Said wall or corrugations 13 will provide a more extended metallic surface for exposure, which will aid also in the diffusion of heat, whereby to render the muffler less subject to the harmful effects of overheating.

The modification shown in Fig. 3 embodies baffle plates 20 constructed with annular flanges 21 that are adapted to be spot welded to the inside of a hollow cylindrical casing 22, whereby to form a muffler. The baffle plates are equipped with apertures 23 and the walls of said baffle plates 20 are corrugated, as at 24, about each of said apertures 23, whereby to strengthen the baffle plates 20, and to provide a more extended surface for the diffusion of heat.

Having thus described my invention what

I claim as new and desire to secure by Letters Patent is:

1. In a muffler for explosive engines, a plurality of sections forming chambers, said sections having their outer edges flared, whereby to nest said sections with relation to each other, said sections having partition walls, the first two partition walls having large central apertures surrounded with walls extending in the direction of flow of the gases for forming an expansion chamber and to aid in diffusing the heat, the remaining partition walls having smaller apertures surrounded with walls extending in the direction of flow of the gases to aid also in diffusing the heat of said gases, and stay rods for holding said sections together.

2. In a muffler for explosive engines a plurality of sections forming chambers, said sections having their outer edges flared, whereby to nest said sections with relation to each other, said sections having partition walls, the first two partition walls having large apertures surrounded with walls extending in the direction of flow of the gases to aid in diffusing the heat, the remaining partition walls having smaller apertures surrounded with walls extending in the direction of flow of the gases to aid also in diffusing the heat of said gases, and stay rods for holding said sections together, and the apertures in said sections being sufficiently large to permit the projection of said stay rods, whereby said stay rods will not make contact with said sections and thereby permit of the expansion and contraction of said sections without bending said stay rods.

In testimony whereof I have affixed my signature.

HERBERT SPENCER POWELL.
